6 Claims. (Cl. 93—51)

This invention relates to apparatus for setting up cartons.

Cartons are often set up from blanks by the use of a die and punch, the punch being reciprocable relative to the die and arranged to press a blank into the die. With some forms of apparatus of this kind a set up carton is removed from the die by suction devices which engage the bottom of the set up carton and withdraw it from the punch and out of the bottom of the die. The provision of such suction devices necessitates the use of reciprocating sucker supports and cams to effect operation thereof, also of pumps or similar devices to provide the necessary suction effects, all of which tend to limit the cyclic speed of operation.

It is an object of the present invention to provide a setting up apparatus which eliminates the use of reciprocating sucker devices and pumps therefor thus reducing speed limitations and permitting the use of carton extracting means operable continuously in one direction.

According to the invention there is provided apparatus for setting up cartons comprising a die open at opposite ends and a punch reciprocable relative thereto to move carton blanks into the die, said die having aligned openings formed in opposite sides thereof and extending lengthwise of the throughway of the die, opposed ejector elements movable in paths parallel with the openings in the sides of the die, and guide elements co-operating with the ejector elements and operable to urge the ejector elements towards each other to press against opposite sides of a carton set up in the die thereby to cause the ejector elements to grip the carton and withdraw it out of the die.

In order that the invention may be clearly understood two embodiments thereof will now be described, by way of example, with reference to the accompanying drawings, in which:

FIG. 1 is a side elevation, partly in section, of the apparatus according to the invention,

FIG. 2 is a section on line II—II, FIG. 1,

FIG. 3 is a view, to an enlarged scale, of a part of FIG. 2,

FIG. 4 is a section on line III—III, FIG. 3,

FIG. 5 is a view showing modifications to the apparatus illustrated in FIG. 2, and

FIG. 6 illustrates an ejector element incorporated in the apparatus of FIG. 5.

Referring to FIGS. 1 to 4 of the drawings, the apparatus comprises a pair of dies 1, 2, FIG. 1, open at the opposite ends thereof, the construction of which is described in United States Patent No. 3,063,348. Reciprocable punches 3, FIG. 2, co-operate with the dies to effect the setting up of blanks therein. The mode of operation of the punches is described in United States Patent No. 3,087,391 and as the punches are withdrawn from the dies the set-up cartons are engaged by stationary spring fingers, not shown, which prevent the carton from following the punches and cause the cartons to remain in the dies.

In accordance with the present invention opposite sides of the die having openings 7, 8, FIG. 2 formed therein. The openings 7, 8 extend lengthwise of the throughway of the die.

2

A carton 9 which has been set up by co-operation between a die and punch is removed therefrom by opposed ejector elements 10, 11, FIGS. 2 and 3, movable in paths parallel with the openings 7, 8 in the sides of the die, and guide elements 12, 13 which co-operate with the ejector elements to urge the ejector elements towards each other to press against opposite sides, FIG. 2 of a carton set up in the die thereby to cause the ejector elements to grip the carton and withdraw it from the punch and out of the die, FIG. 3.

Although in FIG. 1 there are shown two dies and punches together with associated ejector elements the construction of both sets of apparatus is the same and reference to only the one die will hereinafter be made in describing the invention.

The ejector elements 10, 11 are carried respectively by endless chain conveyors 14, 15 and the opposed elements 10, 11 of a pair have, as can be seen in FIG. 3, carton-engaging faces 16, 17 which diverge in the direction of movement of the ejector elements. The chains 14, 15 pass round sprockets 18, 19 and 20, 21 and the tension in the chains is controlled by tensioning sprockets 22 carried by arms 23 pivoted at 24 and urged into engagement with the chains by springs 25. The sprockets 18, 20 are respectively rotatable with shafts 26, 27 driven by chains 28, 29 from a driving shaft 30, FIG. 2.

When, following withdrawal of the plunger as described above, a carton is removed from the die by a pair of ejector elements 10, 11 it is moved downwards by the elements until it is arrested by carton-receiving elements 31, 32, FIG. 2, supported in spaced relation with the die and in the path of the carton. To avoid undue impact of a carton against the elements 31, 32 the linear speed of the chains 14, 15 is reduced as the carton approaches the elements 31, 32. This is effected through the medium of sprocket wheels 33, 34 carried by a bracket 35 pivoted about the driving shaft 30 for rocking movement by a cam 36 rotatable with a further shaft 37 continuously rotatable by means not shown. During a period when a pair of ejection elements 10, 11 is removing a carton from the die a roller 38 carried by the bracket 35 is engaged with the portion 39 of the cam 36, and as the carton is being deposited on the receiving elements 31, 32 the roller 38 is engaged with the portion 40 of the cam. Thus during each of these intervals the sprocket wheels 33, 34 are moved as planets around the sprocket wheel 41 which is rotatable with the driving shaft 30 and so reduce the linear speed of chain 28.

Each ejector element is provided with a projection or heel 42, FIG. 3 and as the ejector elements move downwards from the sprockets 20, 21 the heels 42 are engaged in grooves 43 in the guide elements 10, 11 so that the ejector elements, together with the portion of the chains by which they are carried, are moved towards each other to grip the carton as described above and illustrated in FIG. 3.

The frame members 44, 45, FIGS. 1 and 3, by which the chains 14, 15 are carried co-operate with a shaft 46 having a left-hand screw thread 47 and a right-hand screw thread 48. Thus by applying a spanner to the end 49 of shaft 46 and rotating the shaft the distance between the chains 14, 15 may be adjusted. To accommodate such adjustment the shafts 26, 27 include universal joints 50, FIG. 4.

Cartons delivered on to the carton-receiving elements 31, 32 are moved out of the path of the next succeeding carton by pusher means 51, FIGS. 1 and 2. As shown in the drawings the pusher means 51 are carried by an endless continuously moving conveyor chain 52 and are movable in timed relation with the ejector elements 10, 11 between the carton-receiving elements 31, 32 which extend lengthwise of the conveyor chain 52.

The pusher means 51 are spaced along the conveyor chain 52 that alternate pushers 51 remove cartons delivered from the dies 1, 2.

FIGS. 5 and 6 illustrate a modified embodiment of the apparatus shown in FIG. 2. In this embodiment of the invention the ejector elements 10, 11 each have the shape shown in FIG. 6 and include a step 53. The steps 53 of a pair of ejector elements 10, 11 are provided to prevent cartons which, at the moment of stopping of the apparatus, are in a mid position between engagement and disengagement by the ejector elements from being slowly squeezed out from between the ejector elements and falling uncontrolled, on to the carton-receiving elements 31, 32.

In the embodiments of the invention shown in FIG. 5 the cyclic reduction in linear speed of the ejector elements 10, 11 is effected by co-operating elliptic gear wheels 54, 55 of which the gear wheel 54 is rotatable with a shaft 56 which carries a gear wheel 57 meshing with a gear wheel 58 rotatable with the driving shaft 30, and the gear wheel 55 is rotatable with a shaft 59 carrying a sprocket wheel 60 to drive a chain 61 which in turn drives the chain 29 which rotates the shafts 26, 27. The ratio between the elliptic gear wheels and the drive for shaft 37, and the pitch of the ejector elements 10, 11, is related to the vertical distance between the points of engagement and disengagement of a carton by the ejector elements and the horizontal distance between the dies 1, 2.

I claim:

1. Apparatus for setting up cartons comprising a die open at opposite ends thereof and having aligned openings formed in opposite sides thereof and extending lengthwise of the throughway of the die, a punch reciprocable relative to the die to move carton blanks into the die, opposed ejector elements movable in paths parallel with said openings in the sides of the die and having carton-engaging faces which diverge in the direction of movement of the ejector elements, guide elements cooperating with said ejector elements and operable to urge the ejector elements towards each other to press against opposite sides of a carton set up in the die thereby to cause the ejector elements to grip the carton and withdraw it out of the die, endless conveyors supporting said ejector elements for movement in said paths, driving means operable to effect continuous movement of the conveyors, and control means co-operating with said driving means and operable to reduce the linear speed of the conveyors as a carton is engaged and disengaged by the ejector elements.

2. Apparatus according to claim 1, including carton-

receiving elements supported in spaced relation with the die and in the path of a carton removed from the die by the ejector elements.

3. Apparatus according to claim 2, including pusher means operable in timed relation with the ejector elements to move a carton delivered to the carton-receiving elements out of the path of the next succeeding carton to be delivered to the carton-receiving elements by the ejector elements.

10 4. Apparatus according to claim 3, including an endless conveyor supporting said pusher means for movement therewith, said carton receiving elements extending lengthwise of the pusher-supporting conveyor.

15 5. Apparatus according to claim 1, in which the driving means comprises a rotatable shaft for each endless conveyor, a driven sprocket rotatable with each said shaft, a continuously rotatable driving shaft, a driving sprocket rotatable with the driving shaft, and a chain connecting said driving and driven sprockets, and in which the control means comprises a bracket pivoted on said driving shaft, a cam rotatable in timed relation with the driving shaft and operable to effect rocking of said bracket around the driving shaft, and planetary sprockets carried by said bracket and engaging opposite runs of said chain in close proximity with said driving sprocket, said planetary sprockets being movable by said bracket about the driving sprocket to reduce the linear speed of said chain as the carton is engaged and disengaged by said ejector elements.

20 6. Apparatus according to claim 1, in which the driving means comprises a rotatable shaft for each endless conveyor, a chain coupling sprockets rotatable one with each said shaft, and a driving chain coupling a driven sprocket rotatable with one of said shafts and a driving sprocket rotatable with a first stub shaft, and in which the control means comprises a pair of co-operating elliptical gears one of which is rotatable with the first stub shaft and the other of which is rotatable with a second stub shaft, a continuously rotatable driving shaft, and a pair of meshing gear wheels carried one by the 25 40 driving shaft and one by said second stub shaft.
